UNITED STATES PATENT OFFICE.

GEORGE E. FETZER, OF ST. LOUIS, MISSOURI.

DEVICE FOR TESTING WATER TUBES OF BOILERS.

Application filed July 10, 1925. Serial No. 42,855.

This invention relates generally to improvements in devices for testing water tubes of boilers, and particularly to an improved means whereby the water tubes of a multitube boiler may be individually tested for leaks.

Prior to this invention when it was desired to test the water tubes of the boiler for leaks it was necessary to fill all of the tubes; together with the headers of the boiler, with water. In this way the leaking tube could be located as the water within said leaking tube would escape therefrom, thus providing visible indication of the leak. This method was a time-consuming and expensive one, and I have therefore devised the arrangement disclosed in the present application which comprises means whereby the water tubes of a boiler may be individually tested. In accordance with my invention only the particular tube or tubes which are thought to be leaking are filled with water thus providing for a great saving in time and expense incident to the testing of the tubes.

My invention is of particular importance when a new tube has been placed in a boiler, and it is desired to learn whether or not said tube is watertight. In this event water is placed only in the new tube, thus avoiding the necessity of consuming considerable time and water in filling the entire group of tubes as well as the headers with water.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a fragmentary section through the headers and a water tube of a boiler, showing a pair of my improved devices sealing the opposite ends of said water tube.

Fig. II is a cross section on line II-II of Fig. I.

Fig. III is a cross section on line III-III of Fig. I.

Fig. IV is a cross section on line IV-IV of Fig. I.

Figs. V and VI illustrate in perspective

the cooperating sections of one of the caps of my improved device.

In the drawings, A designates a fragment of a well known type of steam boiler comprising box headers B arranged in communication with each other through the medium of water tubes, only one of which is shown in Fig. I, said water tube being designated by the reference character C. The opposite ends of the water tube C are extended through openings C' in the inner walls of the headers B and are fixed to said inner walls of said headers in the usual manner to provide a watertight joint between said headers and said water tube. D designates handholes in the outer walls of the headers B, said handholes being in longitudinal alinement with the tube C so that access may be had to said tube for the purpose of cleaning same and also so that said tube may be removed and replaced by a new tube when necessary.

By referring to Fig. I of the drawings, it will be seen that one of my improved tube sealing devices is arranged at each end of the tube to be tested, each of said devices including a cap portion 1 which is adapted to enclose an end of the tube C. The cap portion 1 of my improved device is considerably larger in diameter than the tube C and the handholes D, as shown in Fig. I, and as it is necessary to pass said cap portion 1 through one of said handholes into the header when said cap portion is being applied to a tube, it is obvious that some means must be provided to temporary reduce the diameter of said cap portion. In view of the foregoing, I have formed the cap portion 1 of my improved device of two cooperating parts 2 and 3, each of which is of a size that will readily pass through one of the handholes D, said sections of said cap portion being assembled after they have been passed through the handholes and are within the header in which they are to be arranged.

By referring to Figs. V and VI, it will be noted that except for the collar portions forming parts of the cap sections 2 and 3, which collar portions will be referred to later, the sections 2 and 3 are each in the approximate shape of a half-circle, said sections being provided with flat faces 4 which contact with each other when the sections 2 and 3 are assembled. The sections 2 and 3 are each provided with a curved marginal

also because said gasket is made in one piece it will prevent a leakage of water between the cap sections 2 and 3 of the cap.

In the use of my improved water tube sealing device, the water being drained from the boiler, the closure member (not shown) associated with the handhole which is in alignment with the tube to be tested is removed. Also closure members associated with the handholes are removed so that the operator may reach into the interior of the header to assemble the device, as will be described. The separated cap sections 2 and 3 are now passed through one of the handholes D and the operator, having his arms extended through handholes adjacent to the handhole in alignment with the tube to be tested, assembles said cap sections. After the cap sections have been assembled as described, the hollow water conductor which has been extended through the handhole in alignment with the tube to be tested is connected to said cap sections by screwing the threaded end thereof into the threaded opening in the collar portion of the cap section 2 and causing the nut 14 to abut against the collar portion of the cap section 3. The member 15 is then passed through a handhole into the header, and said member 15 is moved laterally with respect to the water conductor 9 so that said water conductor is passed through the opening 16 into the enlarged circular portion thereof at the center of said member 15. After the member 15 is arranged in place as described, the forward reduced portion of the tubular member 17 is passed through the enlarged circular portion of the opening 16 in the member 15, and the threads 19 on the enlarged portion 18 of said tubular member are caused to engage the screw threads within the enlarged circular portion of the opening 16, after which said tubular member 17 is caused to move longitudinally by being rotated until its forward end abuts against the nut 14. As already described, the action of screwing the tubular member 17 inwardly as far as it will go will force the sealing cap into firm contact with the inner face of the inner wall of the header, whereby a fluid-tight joint will be obtained.

After the sealing device provided with the tubular water conductor 9 has been arranged in place as described at one end of the water tube C a similar device is arranged at the opposite end of said tube, the last mentioned device being identical with the first mentioned device, except that instead of a hollow water conductor being employed a solid rod 9' is used, whereby the water is prevented from passing from the tube C through the sealing device provided with said solid rod 9'. Because the last mentioned sealing device is a duplicate of the first mentioned sealing device with the one

exception mentioned, the same reference characters will be used on both devices in the drawings.

When the sealing devices have been arranged in place at the opposite ends of the tube C, a suitable water connection (not shown) is attached to the outer end of the water conductor 9 and water is caused to pass through said water conductor into the tube C, thus providing for the testing of said tube.

I claim:

1. In a testing device for boilers having handholes aligned with tubes, a sealing member adapted to close one end of a tube, a fluid conductor extending from said sealing member to provide for the delivery of fluid to the interior of the boiler tube, a bridge adapted to extend across one of the handholes so as to lie opposite said sealing member, said bridge being narrow enough to pass through the handhole and lie within the boiler, said bridge having a recess in one of its edges to receive said fluid conductor, and a tube extending through said recess to force the sealing member onto its seat, the fluid conductor being surrounded by the last mentioned tube.

2. In a sealing device for boilers, a sealing member in the form of a cap having a flange adapted to surround an end of a boiler tube, said cap being made of separable segmental parts adapted to pass through a handhole of the boiler, an inner tube connecting said segmental parts, a gasket covering the meeting edges of said parts, a bridge adapted to extend across a boiler handhole, said bridge having an opening through which said inner tube extends, and an outer tube extending through said opening to force said cap to its sealing position.

3. In a sealing device of the character described, a sealing member in the form of a cap made of separable segments having meeting edges and provided with overlapping extensions at the central portion of the cap, an inner tube screwed into one of said extensions and having an abutment engaging the other extension to unite said separable segments, a gasket covering the meeting edges of said segments and extending over the peripheral edge of the cap formed by said segments, a bridge member having a recess in one of its edges to receive said inner tube and an enlarged threaded opening communicating with said recess, and an outer tube screwed into said threaded opening and engaging said abutment.

4. In a device for making leakage tests at the junction of a boiler wall and the end of a boiler tube, sealing means to confine a testing fluid, said sealing means including a sealing cap whereby one end of the tube is surrounded to permit communication between the interior of the tube and the surrounded

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.
